A. ANTHONY

WOODWORKING MACHINE

Filed Feb. 7, 1922

Inventor:
Alois Anthony

By Chasimata Stegman
Attorneys.

UNITED STATES PATENT OFFICE.

ALOIS ANTHONY, OF BALTIMORE, MARYLAND.

WOODWORKING MACHINE.

Application filed February 7, 1922. Serial No. 534,652.

To all whom it may concern:

Be it known that I, ALOIS ANTHONY, a citizen of the United States, residing at Baltimore, in the State of Maryland, have 5 invented certain new and useful Improvements in Woodworking Machines, of which the following is a specification.

This invention relates to improvements in wood-working machines, and has for its object to provide a cheap, simple and efficient 10 machine especially adapted for sawing by foot power.

The invention consists of the novel construction and arrangement of the parts and 15 combination of parts hereinafter more fully set forth in the following specification and pointed out in detail in the appended claims.

In the accompanying drawing,—

20 Figure 1 is a side elevation of my invention.

Figure 2 is a top plan view of Figure 1.

Figure 3 is an end view of Figure 1.

Referring to the accompanying drawings, 25 forming part of this specification, and in which like reference numerals designate like parts throughout the several views thereof, 1 designates the table frame which is provided with an adjustable table 2 having one end hinged at 3 and a screw 4 at the opposite end to raise and lower the table 2 with respect to the saw 5. The said saw 5 is mounted on the shaft 6, the latter being mounted in the bearings 7 and 8. The opposite end of the shaft 6 is provided with a pulley 9 connected by the belt 10 with the wheel 11 on the shaft 12. The said shaft 12 is mounted in the bearings 13 and has a wheel 14 on its opposite end of the same 30 size as the wheel 11. The rods 15 are pivoted at one end to the table frame 1 at 16 and are connected at their opposite ends to the wheels 11 and 14 by the bolts 17 which extend through the elongated slots 18 in said rods 15. The treadle 19 has two side pieces 20 which have their ends pivoted to the links 21 which latter are in turn pivoted to the table frame 1 at 22. A rod 23 extends through the rods 15 and side pieces 20 of the

treadle, and also through the end of the arm 50 24. The said arm 24 projects through the bearing 25 and has a coiled spring 26 connected to one end and an adjustable weight 27 at the opposite end, both of which serve to return the arm 24 to its normal position. 55

When the treadle 19 is pressed down against the action of the spring 26 and weight 27, the rods 15 are also forced down causing the wheels 11 and 14 to revolve, and power is transmitted from the wheel 11 60 through the belt 10 to the shaft 6, causing the saw 5 to be revolved. When the treadle 19 is released it will be returned to its normal position by the action of the spring 26 and weight 27, and the same action repeated, 65 thus causing the continuous revolution of the saw 5.

Having thus described my invention, what I claim is:

1. A mechanical movement comprising a 70 frame, a shaft revolvably mounted in the upper part of said frame, two wheels mounted in said frame, a treadle having one end pivoted to said frame, two rods each pivoted at one end to said frame and to said treadle and having elongated slots in their upper ends, bolts passing through said elongated slots of said rods and connecting them with the said wheels, and means connecting one of said wheels with said shaft 75 80 for operating the latter.

2. A mechanical movement comprising a frame, a shaft revolvably mounted in the upper part of said frame, a treadle having one end pivoted to said frame, two rods each pivoted at its lower end to said frame and to said treadle and having elongated slots in their upper ends, bolts passing through said elongated slots of said rods and connecting the said rods with said wheels, means connecting one of said wheels with said shaft 85 90 for operating the latter, an arm mounted in said frame and pivoted near one end to said treadle, a spring connecting one end of said arm with the frame, and an adjustable weight on the opposite end of said arm. 95

In testimony whereof I affix my signature.
ALOIS ANTHONY.
